UNITED STATES PATENT OFFICE.

JOSEPH J. HARRINGTON, OF PHILIPSBURG, MONTANA.

CHUCK-PIN.

1,390,551.

Specification of Letters Patent. Patented Sept. 13, 1921.

Application filed March 28, 1921. Serial No. 456,261.

To all whom it may concern:

Be it known that I, JOSEPH J. HARRINGTON, a citizen of the United States, residing at Philipsburg, in the county of Granite 5 and State of Montana, have invented certain new and useful Improvements in Chuck-Pins, of which the following is a specification, reference being had to the accompanying drawings.

10 This invention relates to improvements in chuck pins and has for an important object thereof the provision of a pin which may readily be removed from the chopping block.

15 In its usual form the chuck pin consists in a tapered pin having a hole near the top. In use the chuck pin is inserted through the piece of meat which it is desired to secure in position upon the block, and driven into 20 the wood of the chopping block. When it is desired to remove the same a steel or similar implement is inserted in the hole or the pin rotated until free from the block. As will be obvious, this manner of releasing the pin 25 has a tendency to enlarge the hole to a size at which the steel no longer is effectual for rotating the pin and accordingly it becomes necessary to employ a wrench. Furthermore, the blow struck upon the upper end 30 of the pin to drive the same into the wood will distort the pin at the point where it is weakened by the hole. In accordance with my invention I provide as an article of manufacture, a tapered pin such as is commonly employed, provided with a pivoted 35 handle, the pin and handle having means whereby the movement of the handle is limited when the handle has reached a desired elevation so that pressure may be exerted upon the handle both to rotate the pin and to elevate the same, the handle normally lying substantially parallel to the pin.

Other objects and advantages of the invention will become apparent throughout the course of the following description.

In the accompanying drawings, wherein for the purpose of illustration is shown a preferred embodiment of my invention and 50 wherein like reference characters designate like parts throughout,

Figure 1 is a perspective view showing a chuck pin constructed in accordance with my invention in position on a chopping 55 block.

Fig. 2 is a side elevation of the pin with the handle removed.

Fig. 3 is a similar view taken at right angles to that shown in Fig. 2.

Fig. 4 is a detached view of the handle and

Fig. 5 is a sectional view taken through the handle and pin.

Referring now more particularly to the drawings, the numeral 10 indicates a chucking pin of substantially the same construction as those usually employed, being tapered longitudinally and pointed upon its lower end, as at 11, the upper end of the pin being fairly heavy and being adapted for 65 the reception of a blow from a cleaver or similar implement, whereby it may be driven into the chopping block.

The numeral 12 indicates a lug formed on the side of the pin adjacent the upper 75 end thereof and having an opening 13 formed therein adapted for the reception of a pivot pin 14. This pivot pin likewise extends through arms 15 formed by the furcation of one end of a handle member 80 16 to pivotally connect the handle member 16 to the pin. The handle member 16 is provided adjacent its pivot point with a shoulder 17 adapted to coact with a stop-shoulder 18 formed upon the lug 12 to check 85 the rotary motion of the handle 16 upon its pivot when the handle is approximately at right angles to the pin. The handle normally lies substantially parallel to the pin 10, assuming this position by gravity. 90 It will be noted that when the handle is moved to the elevated position, pressure may be brought to bear upon the pin, thereby not only to rotate the pin but to elevate the same so that the pin may be readily removed from the chopping block. 95

As many changes in the shape, size and arrangement of the various parts hereinabove set forth are possible without departing in any manner from the spirit of my 100 invention, I do not limit myself to the specific structure thereof except as herein-after claimed.

What I claim is:

1. As a new article of manufacture, a 105 chuck pin having a handle pivotally connected thereto adjacent the upper end thereof, and means for limiting the pivotal movement of the handle with relation to the pin.

2. In an article of manufacture, a chuck 110

pin having a lug extending outwardly therefrom, a handle pivotally connected with the lug, a shoulder formed upon said handle, and a stop-shoulder formed upon the lug and with which said handle engages when said handle is disposed at approximately right angles to said pin.

3. As a new article of manufacture, a chuck pin provided upon the upper end thereof with an outstanding lug having an opening formed therein adapted for the

reception of a pivot pin, a handle having one end thereof furcated to form spaced arms, said arms likewise being provided with openings through which the pivot pin 15 extends, and a shoulder extending outwardly from said lug and with which said handle engages to limit the rotation thereof upon the pivot point in one direction.

In testimony whereof I hereunto affix 20 my signature.

JOSEPH JERIMAH HARRINGTON.
